UNITED STATES PATENT OFFICE

WALTER C. ULINE, OF NAPPANEE, INDIANA

MACHINE FOR ASSEMBLING LADDER PARTS

Application filed March 13, 1931. Serial No. 522,405.

My invention relates more particularly to machines for assembling the step-forming parts of ladders with the side-bars thereof; and my primary objects, generally stated, are to provide a machine by means of which the assembling operation may be performed quickly and economically; and to provide a simple and economical construction of machine for this purpose; and other objects as will be manifest from the following description.

Referring to the accompanying drawings:

Figure 1 is a plan view of a machine embodying my invention.

Figure 2 is a view in side elevation thereof.

Figure 3 is an enlarged end view of the machine, the machine being viewed from the left-hand side of Fig. 2.

Figure 4 is a broken longitudinal sectional view of the machine, the section being taken at the line 4—4 on Fig. 3 and viewed in the direction of the arrows.

Figure 5 is a section taken at the irregular line 5—5 on Fig. 4 and viewed in the direction of the arrows the ladder parts to be assembled being shown as located in the machine, but in disassembled position.

Figure 6 is a view like Fig. 5 and of the structure therein showing the ladder parts in assembled position.

Figure 7 is a broken section taken at the line 7—7 on Figs. 5 and 8 and viewed in the direction of the respective arrows, this view being an enlargement of the parts represented in Fig. 5.

Figure 8 is a section taken at the line 8—8 on Fig. 7 and viewed in the direction of the arrows.

Figure 9 is an enlarged broken section taken at the line 9—9 on Fig. 6 and viewed in the direction of the arrows; and

Figure 10, a face view of the completed ladder the side bars and step-forming parts of which are assembled by the machine of the preceding figures.

As a preface to a description of the machine, it may be stated that an example of a ladder to be made on the machine is illustrated in Fig. 10, the ladder being of a construction comprising a riser section 11 and a rear

leg section 11^a hingedly connected together at their upper ends adjacent a platform section 11^b, the riser section 11 comprising side bars 12, tension rods 13 connecting the bars 12 together in the desired spaced apart condition and step-forming boards 14 which fit at their ends in gains 15 in the inner faces of the bars 12.

The machine shown is provided for the purpose of assembling with the side bars 12 to which the rods 13 have been connected as shown in Fig. 10, the step-forming boards 14 which, in accordance with the particular machine shown, are simultaneously forced to position into the gains 15.

The machine comprises a frame formed of end members 16, upper side bars 17 and lower side bars 18 vertically adjustably mounted on the end members 16 by bolts 19 extending through vertically elongated slots 20 in the end members 16.

Located at the inner sides of the bars 17 in spaced apart position therealong are supports 21 in the form of blocks, for the assembled side bars 12 and tension rods 13. The blocks 21, which are of angle shape as shown and support the side bars 12 at their horizontal flange portions 22, are mounted on the inner ends of rods 23 slidable in the bars 17 and normally outwardly pressed by coil springs 24 which surround the rods 23 and bear at opposite ends, respectively, against the outer sides of the bars 17 and nuts 25 on these rods.

The machine also comprises means for receiving the step-forming boards 14 and forcing them into the gains 15 to the position shown in Fig. 6, these means comprising the following mechanism.

Located beneath the blocks 21 is a vertically movable frame formed of parallel bars 26 secured together by tie rods 27 with spacer sleeves 28 surrounding the rods 27 and located between the bars 26, the latter being provided at their outer faces with plates 29 secured thereto by screws 30.

The plates 29, shown as notched at their upper edges as indicated at 31, to receive the lower edges of the step-forming boards 14, are slidable in inclined grooves, or slideways,

32 in blocks 33 rigidly secured to the inner sides of the frame bars 17, the blocks 33 containing grooves, or slideways, 34 parallel with, and opening through the bottoms of, the grooves 32, the grooves 34 containing blocks 35, adjustable, as by the screws 36 which have threaded engagement with the bars 35 and set screws 37 which flatwise bear against these bars, for the purpose of adjusting the machine for operation on step-forming boards 14 of different lengths.

It may be here stated that in the use of the machine the ladder side bars 12 with the tension rods 13 assembled together as shown are applied to the position shown in Figs. 4 and 5 to rest at the side bars 12 on the horizontal portions 22 of the blocks 21 between the side bars 17 and vertical flanges 38 on the blocks 21, the outer faces of the flanges 38 being inwardly inclined as represented at 39, the parts being so proportioned and arranged that in positioning the ladder parts as above described the side bars 12 will extend in oppositely tilted position as shown in Fig. 5, namely, in a position in which they converge upwardly crosswise of the ladder structure. The step-forming boards 14 to be assembled with the side bars 12 are inserted at their ends into the grooves 34 and seat at their lower edges upon the frame comprising the bars 26, the grooves 34 inclining in the same direction and at the same angle as the gains 15 in the ladder sides 12 and being so disposed that when the ladder sides 12 are applied to the machine in the position above noted, the several step-forming boards 14 will be lined up crosswise with the several pairs of opposed gains 15, respectively. Thus, the several step-forming boards 14 may be simultaneously shifted to cause them to extend at their ends into the several pairs of gains and thus assemble them with the side bars 12 of the ladder construction, by bodily lifting the frame of which the bars 26 are parts.

The machine shown comprises means for thus actuating the frame referred to the particular illustrated means for this purpose comprising rock members 40 located at different points along the machine and coincident with its median line as shown and journaled in the side bars 18, the members 40 having pairs of spaced apart arms 41 at opposite ends thereof between which rollers 42 positioned directly beneath the bars 26, are journaled.

Each member 40 is provided with an arm 43 extending at an angle to the arms 41 and pivoted at 44 to a horizontal reciprocable bar 45 connected at one end with means for reciprocating it and shown as comprising a piston and cylinder mechanism represented generally at 46, the cylinder 47 of which is trunnioned at 48 to brackets 49 vertically adjustably secured to the adjacent end member 16 of the frame of the machine, the piston

of the mechanism 46 and shown at 50 being connected with a piston rod 51 pivoted at its outer end to the bar 45 as represented at 52.

The piston 50 is adapted to be reciprocated by fluid pressure introduced into the opposite ends of the cylinder 47 alternately, the fluid at the end of the cylinder toward which the piston is operated being permitted to exhaust. As such mechanism, with means for controlling its operation, is of common and well known construction detailed illustration and description thereof appears to be unnecessary, it being sufficient to state that the cylinder 47 is associated with valve mechanism represented at 53 which communicates with a pipe 54 for leading the operating fluid pressure into the valve 53 and pipes 55 and 56 leading from the valve mechanism 53 to the opposite ends of the cylinder 47, the handle 57 by which the valve 53 is operated to alternately direct fluid pressure into the opposite ends of the cylinder 47 and exhaust it therefrom, as stated, being represented at 57.

It will be understood from the foregoing that when the valve handle 57 is swung in one direction fluid pressure will enter the cylinder 47 at one end, the fluid in the opposite end of the cylinder exhausting through the valve 53 and the bar 45 being moved lengthwise in one direction; and when the handle 57 is moved in the opposite direction the fluid pressure enters the other end of the cylinder 47, the fluid pressure previously introduced therein being exhausted through the valve 53 and the bar 45 is moved lengthwise in the opposite direction.

The machine also comprises means movable into and out of a position overlapping the upper edges of the ladder side bars 12 for the purpose of preventing the latter from becoming upwardly displaced in the step-board-inserting operation above referred to, these means in the particular construction shown comprising plates 58 located at different points along the bars 17 and movable crosswise thereof into and out of the position shown by full lines in Fig. 6. The plates 58 are slidably mounted in channels 59 in brackets 60 secured to the side bars 17, these brackets having cover plates 61 secured thereto and extending over the plates 58, the plates 58 being provided at their undersides with racks 62 which mesh with pinions 63 secured to shafts 64 located at opposite sides of the machine and journaled in the brackets 60.

The shafts 64 are connected together by means which operate when one shaft is rotated, as by means of a hand lever 65 on one of the shafts 64, to cause the other of these shafts to rotate in the reverse direction thereby simultaneously moving the plates 58 at both sides of the machine into operative position (Fig. 6) when the lever equipped shaft

referred to is rocked by actuating the lever 65 in one direction and out of operative position when this lever is rocked in the opposite direction, the means shown for the 5 purpose just stated comprising a pair of cables 66 arranged in crossed relation as shown and pivoted at heads 67 on their ends to crank pins 68 provided on disks 69 secured to the shafts 64 at one end of the machine.

10 In the use of the machine, assuming the parts thereof to be in the position shown in Fig. 5, fluid pressure is introduced into the cylinder 47 to shift the bar 45 to the left in Fig. 4 to the position shown in Figs. 2 and 15 6, which raises the frame comprising the bars 26, thereby raising and forcing the step-forming boards into the gains in the ladder side bars to the position shown in Fig. 6.

The positioning of the ladder side bars 12 20 in upwardly converging relation as shown in Fig. 5 permits of the ready entry of the step-forming boards into the gains 15, the side bars 12, as the boards move in the gains, swinging against the yielding tension of the 25 springs 24 outwardly at their upper edges and inwardly at their lower edges, on the tension rods, which latter in the final positioning of the boards in the gains are in tensioned condition.

30 Initial positioning of the step-forming boards at different elevations and the extent of upward movement of the board-elevating frame, to adapt the machine for use with 35 boards of different widths and to provide for the final positioning of these boards in the gains, in the desired position relative to the faces of the riser section of the ladder, are provided for in the machine by certain of the described adjustments which, while shown 40 as of a particular type and exemplified by the vertical adjustment of the side bars 18 and the piston and cylinder mechanism, may be provided for in any other suitably way if desired.

45 While I have illustrated and described a particular construction of machine embodying my invention I do not wish to be understood as intending to limit it thereto as the same may be variously modified and altered, 50 as for example as above suggested with regard to certain of the adjustments, without departing from the spirit of my invention.

What I claim is new, and desire to secure by Letters Patent, is:

55 1. In a machine of the character set forth, the combination of means for supporting ladder side-bars in spaced apart relation and having grooves in opposite surfaces thereof, and means for introducing step-forming elements into said grooves in a direction lengthwise of said grooves.

60 2. In a machine of the character set forth, the combination of means for supporting ladder side-bars in spaced apart relation and 65 having grooves in opposite surfaces thereof,

and means for simultaneously introducing step-forming elements into said grooves in a direction lengthwise of said grooves.

3. In a machine of the character set forth, the combination of means for supporting 70 ladder side-bars in spaced apart relation and having grooves in opposed surfaces thereof, means for introducing step-forming elements into said grooves in a direction lengthwise of said grooves, and means movable into and 75 out of a position for resisting displacement of said side-bars in the operation of said second-named means.

4. In a machine of the character set forth, the combination of means for supporting 80 ladder side-bars in spaced apart relation and having grooves in opposed surfaces thereof, means for simultaneously introducing step-forming elements into said grooves in a direction lengthwise of said grooves, and means 85 movable into and out of a position for resisting displacement of said side-bars in the operation of said second-named means.

5. In a machine of the character set forth, the combination of means for supporting 90 ladder side-bars in spaced apart relation and tied together by tension rods and having grooves in opposed surfaces thereof, means yieldingly holding said bars in relatively tilted position crosswise of the length of said 95 bars, and means for introducing step-forming elements into said grooves in a direction lengthwise of said grooves.

6. In a machine of the character set forth, the combination of means for supporting 100 ladder side-bars in spaced apart relation and tied together by tension rods and having grooves in opposed surfaces thereof, means yieldingly holding said bars in oppositely tilted position crosswise of the length of said 105 bars, and means for introducing step-forming elements into said grooves in a direction lengthwise of said grooves.

7. In a machine of the character set forth, the combination of means for supporting 110 ladder side-bars in spaced apart relation and tied together by tension rods and having grooves in opposed surfaces thereof, said means comprising yieldable members having 115 portions engaging said bars and holding the latter in oppositely tilted position crosswise of the length of said bars, and means for introducing step-forming elements into said grooves in a direction lengthwise of said 120 grooves.

8. In a machine of the character set forth, the combination of means for supporting ladder side-bars in spaced apart relation and having grooves in opposed surfaces thereof, and means for introducing step-forming elements into said grooves in a direction lengthwise of said grooves, said first and second 125 named means being relatively adjustable toward and away from each other.

9. In a machine of the character set forth,

said side-bars, and means for actuating the shiftable one of said means.

21. In a machine of the character set forth, the combination of means for supporting ladder side-bars in spaced apart relation and having grooves in opposite surfaces thereof, means for supporting a step-forming element in alinement with the grooves in said side-bars, said last-named means being adapted to be shifted in a direction lengthwise of said grooves for introducing the ends of said element into said grooves, and means for shifting said last-named means.

22. In a machine of the character set forth, the combination of means for supporting ladder side-bars in spaced apart relation and having grooves in opposite surfaces thereof, means for supporting a step-forming element in alinement with the grooves in said side-bars, one of said means being adapted to be shifted in a direction lengthwise of said grooves for assembling said element with said side-bars, and means movable into and out of a position for resisting displacement of the side-bars in the relative movement of said first and second named means.

23. In a machine of the character set forth, the combination of means for supporting ladder side-bars in spaced apart relation and tied together by tension rods and having grooves in opposed surfaces thereof, means yieldingly holding said bars in oppositely tilted position crosswise of the length of said side-bars, and means for supporting a step-forming element, said first and third means being relatively movable in a direction lengthwise of said grooves, for entering the ends of said element into said grooves.
